UNITED STATES PATENT OFFICE.

CHARLES W. LOUFERK, OF CEDAR RAPIDS, IOWA, ASSIGNOR TO THE CORNO MILLS COMPANY, OF EAST ST. LOUIS, ILLINOIS, A CORPORATION OF ILLINOIS.

CAPPING MACHINE.

Application filed July 8, 1926. Serial No. 121,143.

This invention relates to a capping machine adapted to apply caps to cartons and other receptacles.

One of the objects is to reduce or eliminate the losses due to failure of the caps to properly fit onto the receptacles during the capping operations. In one form of the invention, a guiding device is used to hold the cap in alignment with the receptacle, and this guiding device is provided with a projection adapted to lie directly between the cap and receptacle. The projection may be in the form of a thin flange surrounded by the lower margin of the cap and serving as a guide to positively direct one end of the receptacle into the cap, as will be hereafter described.

Another object is to produce a simple and effective means for delivering the caps and receptacles to the devices which apply the caps. To illustrate this feature I have shown and will hereafter describe a pair of endless conveyors feeding the caps and receptacles to stop members located near the cap-applying devices, and a pair of pushers whereby the caps and receptacles are moved from the conveyors to the cap-applying devices.

Another object is to cause the cap to adhere to the receptacle by properly applying a suitable amount of adhesive gum, or the like, to the cap-receiving end of the receptacle. In carrying out this object I prefer to utilize a gumming roll located above a traveling conveyor whereby the receptacles are carried toward the capping device, and it is convenient to have a stop in the course of the receptacles to permit motion of the conveyor while some of the receptacles are at rest. However, if a receptacle is at rest, or subjected to an intermittent motion, while in contact with the gumming roll, an excess of gum will be delivered to the receptacle and the distribution of the gum will not be uniform. Attention will be hereafter directed to a means whereby the receptacles are given a uniform motion and prevented from stopping while in contact with the gumming roll.

A further object is to provide an improved means for holding and dropping the receptacles in a guide, where they are re-

leased one at a time and then delivered to the cap-applying mechanism.

With the foregoing and other objects in view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which come within the scope of the claims hereunto appended.

Fig. I is a top view of a capping machine embodying the features of this invention.

Fig. II is a side elevation of the machine.

Fig. III is a vertical section on a larger scale taken approximately, but not exactly, on the line III—III in Fig. II.

Fig. IV is a top view, partly in section, illustrating various elements near the points where the caps are applied to the receptacles.

Fig. V is an enlarged fragmentary vertical section showing the means for directing the cap-receiving ends of the receptacles into the caps.

Fig. VI is a section on a still larger scale showing one of the guiding elements between the receptacle and the cap.

Fig. VII is a view similar to Fig. IV illustrating certain elements which lie in a higher plane.

A designates receptacles in the form of paper tubes, or cartons, adapted to receive a cap at each end. I will hereafter describe the manner in which the caps are applied to one end of each tube, and it is to be understood that the other end may be capped in the same manner. The tubular receptacles enter the apparatus through a vertical guide B (Figs. I and II) where they drop by gravity to a feeding device consisting of several elements which transmit them to the capping mechanism. The vertical guide B comprises rods 1 connected by rings 2 which surround the rods. A stationary platform 3 is located below this vertical guide, and a feeder 4 reciprocates above the platform, said feeder having a horizontal extension 5 at the top onto which the receptacles are dropped, as will be hereafter described. The feeder 4 is provided with lugs

6 slidably mounted on horizontal rods 7. An endless traveling conveyor 8 is arranged below the stationary platform 3 to receive the receptacles pushed therefrom by the reciprocating feeder 4.

The means for controlling the delivery of the receptacles from the vertical guide B comprises a primary retarding lever 9 fulcrumed at 10 and having a curved arm 9' 10 engaging the lowermost receptacle A in the guide B. A secondary retarding lever 11 is pivoted at 12 and provided with a curved arm 13 adapted to engage the side of the receptacle to force the receptacle into frictional engagement with the vertical guide. A link 14 connects the lever 11 to the lever 9, the latter being connected to an arm 15 extending from an eccentric strap 16 surrounding an eccentric 17 on a constantly 20 rotating shaft 18. The reciprocating pusher 4 is connected by means of a link 19 (Figs. I and II) to a crank arm 20 on the shaft 18.

The operation of the elements just described is as follows:

25 During each revolution of the shaft 18 the lever arm 9' is displaced from the guide B to release the lowermost receptacle, and the lever 11 is moved to frictionally engage the side of the next higher receptacle. 30 When this occurs the horizontal extension 5 on the feeder 4 lies below the vertical guide and the lowermost receptacle drops onto said extension, while the next higher receptacle is frictionally held by the lever 11. 35 During the return stroke of the feeder 4 the receptacle drops from the lower end of the vertical guide B to the stationary platform 3, and the lever 9 is restored to the position shown in Fig. II, while the upper lever 11 is 40 restored to release the receptacle above the lever arm 9'.

As these operations are continued the receptacles are pushed from the stationary platform to the traveling conveyor belt 8.

45 The means for driving the shaft 18 on which the crank arm 20 and eccentric 17 are mounted comprises a pulley 21 fixed to a shaft 22 and driven by the conveyor belt 8, a sprocket wheel 23 fixed to said shaft 22, 50 a sprocket wheel 24 fixed to the shaft 18, and a sprocket chain 25 transmitting motion from the wheel 23 to the wheel 24. When the machine is in operation, these elements are driven continuously to release the receptacles from the vertical guide and to transmit them to the traveling conveyor belt 8 which carries the receptacles to the opposite end of the machine. The upper portion of this belt travels in a channel 26, and said 55 belt is driven by a pulley 27 shown in Figs. II and IV.

The means for imparting motion to the belt 8 comprises a shaft 28 (Fig. IV) on which the pulley 27 is mounted, a gear wheel 29 fixed to said shaft and meshing with a

gear wheel 30, the latter being on a shaft 31 provided with a sprocket wheel 32. This sprocket wheel 32 is driven by a chain 33 (Figs. I and IV) extending from a driving sprocket wheel 34 on a power shaft 35 which 70 may be operated by any suitable power.

The conveyor belt 8 is thus driven to carry the receptacle A to a stationary stop bar 36, which appears in Figs. I, IV and VII. When the machine is in operation the receptacles are temporarily stopped by the bar 36 while the conveyor belt continues in motion beneath them, and to provide an ample supply of receptacles for quick delivery to the capping device, a row of these receptacles is 80 formed, as shown at the left portion of Fig. II, the receptacle at the extreme left of the row being in contact with the stationary stop bar 36 which appears in Fig. I.

Figs. I and II show a rotary gumming 85 roll 37 located above the course of the receptacles A and adapted to contact with the upper edges thereof. This roll transfers adhesive gum from a pan 38 to the receptacles. The roll is fixed to a shaft 39 provided with a sprocket wheel 40 driven by a chain 41 extending from a larger sprocket wheel 42 on a shaft 43, the latter having a second sprocket wheel 44 driven by a chain 45 passing around a sprocket wheel 46 on the power shaft 35. The peripheral speed of the gumming roll 37 is preferably the same as the speed of the conveyor belt 8 which carries the receptacles past the gumming roll. 90

This is a simple and convenient means for applying adhesive material to the cap-receiving ends of the receptacles, but to obtain an even distribution of the gum the receptacles should not be permitted to stop while in contact with the rotary gumming roll. 100 They are stopped and permitted to accumulate at the left of this roll, as shown in Fig. II, but they are retarded at the right of the roll and released one at a time in response to each capping operation, as will be presently described, so a constant and uniform motion is imparted to the receptacle in contact with the gumming roll. 105

A suitable means for stopping and releasing the receptacles at the right of the gumming roll 37 is shown in Figs. I and II. It comprises a wheel 47 having radial stop arms movable into and out of the course of the receptacles passing to the gumming roll. This wheel 47 may be loosely mounted on a shaft 48 located at one side of the traveling conveyor belt 8. A controlling lever 49, pivoted at 50, is oscillated by a long bar 51, as will be hereafter described, and the upper end of this lever moves into and out of the path of the radial arms on the stop wheel 47. This loosely mounted wheel may be driven by the receptacles A on the conveyor belt 8, so as to allow the receptacles to pass the wheel, but said wheel is stopped 115 120 125 130

and released by the upper end of lever 49. During each capping operation the lever 49 is moved to release the stop wheel 47, and after a slight motion of the free wheel the upper end of the lever again enters the path of the wheel to prevent release of more than one receptacle.

The means for operating the controlling lever 49 includes a bell crank lever 52 (Figs. I, III and IV) connected to the long bar 51 and provided with a slotted end to receive an operating pin 53 projecting from a lever arm 54. This lever arm 54 is oscillated during each of the capping operations to be hereafter described, and it is therefore a convenient means for transmitting motion to the elements just described. However, it is to be understood that the invention is not in any way limited to this particular means for transmitting the desired motion.

The caps C enter the apparatus through a chute 55 (Figs. I, II and III) and they slide onto the lower portion of a constantly moving conveyor belt 56, said belt being mounted on pulleys 57 and 58. The pulley 57 is secured to the shaft 43 on which the sprocket wheel 44 is mounted (Fig. I) to transmit motion to said shaft.

In Fig. II a portion of the conveyor belt 56 is shown in section, and it will be noted that this belt surrounds the caps C resting upon the lower portion thereof. The caps move to the left in Fig. II and the cap at the extreme left is stopped in the course of a pusher which transfers the caps to the capping device, as will be hereafter described. The means for stopping the caps C in the conveyor belt 56 comprises a stationary stop bar 59, which is shown most clearly in Fig. VII, and a movable stop bar 60 carried by the cap-pusher, which will be presently described.

The belt 56 lies directly above the conveyor belt 8 on which the receptacles travel, and the stationary stop bar 59 for the caps lies above the stationary stop bar 36 for the receptacles, as indicated in Fig. VII. These bars are intended to stop a cap and a receptacle in the course of reciprocating pushers which travel in lines at a right angle to the belts, so as to simultaneously feed a cap and a receptacle to the capping device.

The reciprocating pushing device comprises a horizontal plate 61 (Figs. I, III, IV and VII) having its side edges slidably mounted in guides 62. The cap-pusher comprises a long arm 63 extending from the plate 61 and terminating in a curved cap-engaging member 64. This arm 63 and its curved member 64 are adapted to travel through the cap-feeding belt 56 (Figs. III and VII) so as to remove a cap from the stationary stop bar 59 and push the cap from said belt. The curved member 64 (Figs. IV and VII) carries the stop bar 60 which restrains the

next adjacent cap until the pusher is restored by moving to the right from the position shown in Fig. VII. Angle bars 65 (Figs. III and VII) prevent displacement of the cap C engaged by the movable stop bar 60.

The means for pushing the receptacles from the lower belt 8 is shown in Figs. III and IV. It comprises the reciprocating plate 61 and a member 66 at one end of this plate adapted to contact with a receptacle A, as shown in Fig. III. The contact member 66 may be formed integral with the reciprocating plate. In Fig. III the member 67 is a reinforcing web uniting said plate and the contact member 66. This contact member 66 conforms to the shape of the cap-engaging member 64 and it lies directly below said member 64. It travels over the top of the lower belt 8 to push a receptacle 85 from the stationary stop bar 36 which appears in Figs. I, IV and VII.

The means for reciprocating the slidable plate 61 and the pushers carried thereby includes a horizontal pin 68 (Fig. III) carried by said plate and located in the forked upper end of the lever arm 54, said arm being fixed to a shaft 69 (Figs. I and III) provided with an operating arm 70 connected by means of a rod 71 to a crank 72 on a rotary shaft 73, which will be hereafter referred to.

Before pointing out the details of the capping device I will state that it comprises a pair of semi-cylindrical gripping members 74 movable away from each other to receive the cap and receptacle from the pushers 64 and 66, and these gripping members are movable toward each other to frictionally hold the cap and receptacle. They 105 form a guiding device to align the cap with the receptacle, and when so aligned and frictionally held, the cap and receptacle are acted upon by plungers 75 and 76 to apply the cap to the receptacle.

Each semi-cylindrical member 74 is formed integral with a horizontal plate 77 (Figs. II, III and V) having its side edges slidably mounted in stationary guides 78. The means for moving these semi-cylindrical members toward and away from each other comprises levers 79 (Figs. II and III) having forked upper ends to receive pins carried by the sliding plates 77. These levers 79 are fulcrumed at 80 and they have 115 rollers at their lower ends (Fig. II) engaging cams 81 on the rotary shaft 73. The cams move the levers 79 to force the semi-cylindrical members 74 toward each other, and springs 82 may be employed to move 125 said members 74 away from each other.

Fig. III shows that a horizontal surface is provided to support the receptacles A when they are pushed from the belt 8 to the plunger 76 where the capping operation is 130

performed, but a special movable support is provided for the caps C passing from the belt 56 to a point below the upper plunger 75. This movable support is adapted to 5 retain the cap in an elevated position between the semi-cylindrical gripping jaws until said jaws frictionally hold the cap. The support referred to comprises a pair of supporting wings 83 (Figs. III and 10 IV) pivoted at 84 and having extensions 85 connected by links 86 to the reciprocating gripping jaws 74. Each of these jaws is slotted at 87 (Figs. III and V) to receive one of the supporting wings 83. The wing 15 83 in each of the jaws 74 (Fig. IV) is connected to the other jaw by means of one of the links 86. Bearing in mind that each wing 83 is connected to a stationary pivot 84 (Fig. IV) near one of the gripping jaws 20 74, and that a link 86 connects the wing to the other gripping jaw, the motion suggested by dot and dash lines in Fig. IV will be readily understood. The jaws 74 move toward and away from each other in straight 25 lines, while the supporting wings 83 swing on the pivots 84.

When the jaws 74 are separated as shown by full lines in Fig. IV, the wings 83 occupy the positions shown by full lines to 30 receive a cap delivered by the reciprocating pusher 64, and as the jaws approach each other to grip the cap, the wings 83 gradually move out of the jaws to the positions shown by dot and dash lines.

35 It will now be understood that a cap C is located above a receptacle A as shown in Fig. III, and that the semi-cylindrical gripping jaws 74 then move toward each other to frictionally hold the cap and receptacle in alignment with each other. By mechanism 40 to be hereafter described, the top plunger 75 moves down to the position shown in Fig. V, and the lower plunger 76 moves upwardly to insert the upper end of the receptacle into 45 the cap. An important feature is to be considered at this point.

The cap and receptacle may be made of paper or other more or less flexible material, and a high degree of accuracy is not obtained 50 in the manufacture of such articles. The shape and dimensions vary more or less but the cap is intended to rather closely fit the receptacle.

55 Figs. III, IV, V and VI show that the means for applying the cap comprises a vertical guiding device including jaws 74 which frictionally hold the cap and receptacle in alignment with each other, and a projection 60 88 adapted to lie directly between the cap and receptacle when they are moved from the position shown in Fig. III to the position shown in Figs. V and VI. Each gripping jaw 74 is cut away to receive a semi-cylindrical bar 89 which may be secured by means 65 of screws 90, and the guiding projection 88

may be in the form of a thin flaring flange of arcuate formation extending upwardly from the bar 89. When the gripping jaws 74 lie adjacent to each other, the flanges or projections, 88 provide a substantially circular guiding element to direct the receptacle into the cap.

The flaring flange 88 extends inwardly from the internal friction surfaces of the gripping jaws, so as to provide a recess to 75 receive the lower margin of the cap C, and after the upper plunger 75 moves downwardly to locate this margin in the recess the lower plunger 76 moves upwardly to force the upper margin of the receptacle into 80 the cap. This upper margin may be slightly contracted in moving across the rigid metal flange, or projection, 88 and it is positively directed into the cap which surrounds said flange. Thereafter the lower 85 plunger 76 continues its upward motion to withdraw the cap C from the flange 88, and the gripping jaws 74 then move away from each other to release the flange and jaws from the capped receptacle. When the next 90 receptacle enters the space between the gripping jaws, it pushes the capped receptacle from said space.

The inner face of each gripping jaw 74 is provided with an opening 91 (Figs. III, 95 IV, V and VI) in the form of a vertical channel or groove, and when the jaws are in their capping positions their adjacent edges are slightly separated as shown at 91' in Figs. IV and V, to form additional openings at the friction faces. These openings lie in the course of the flange on the cap and they are intended to receive bulging portions of this flange. I have found in practice that some of the paper cap flanges are too 100 large in diameter, and that a flange of about the proper diameter may have a bulging portion. In either of these cases the pressure of the gripping jaws is likely to cause the flange of the cap to bulge inwardly unless 105 there is some provision to receive an outward bulge or wrinkle. If a part of the cap-flange extends inwardly, the cap will not properly receive the receptacle. The openings 91 and 91' therefore aid in permitting the cap-flange to bulge outwardly where 110 it will not interfere with either the receptacle or the guiding member 88 which directs the receptacle into the cap.

The means for operating the capping 115 plungers 75 and 76 comprises a rod 92 extending downwardly from the lower plunger 76 and provided with a roller at its lower end engaging a cam 93 on the rotary shaft 73. This rod 92 moves in a stationary guide 94 (Figs. II and III) which is slotted at 95 to receive a pin extending from the rod to prevent rotation of the vertically movable rod.

The upper plunger 75 is fixed to a rod 96 130

(Figs. II and III) slideable in a stationary guide 97 and having an annular groove at its upper end to receive a lever 98, the latter being fulcrumed at 99 (Fig. II) and provided with a spring 100 tending to retain the plunger 75 in its elevated position. The lever 98 is actuated by means of a vertical rod 101 (Fig. II) slideable in guides 102 and adapted to contact with said lever. The lower end of rod 101 carries a roller contacting with a cam 103 on the rotary shaft 73. This cam 103 appears in Figs. II and III, but the rod 101 is broken away in Fig. III for the cam and rod are near one end of the shaft 73, and most of the other elements in Fig. III conform approximately to the section line III—III in Fig. II.

The means for rotating the shaft 73 comprises a bevel gear 104 on one end of said shaft meshing with a bevel gear 105 on the power shaft 35.

I claim:

1. In a machine for applying caps to receptacles, a guiding device adapted to hold the cap in alignment with the receptacle, said guiding device being provided with a rigid projection of arcuate form disposed within the cap and adapted to lie directly between the overlapping walls of the cap and receptacle.

2. In a machine for applying caps to receptacles, a guiding device adapted to hold the cap in alignment with the receptacle, said guiding device being provided with a rigid internal projection of arcuate form adapted to lie directly between the cap and receptacle, and operating means whereby the cap and receptacle are located at opposite sides of said projection.

3. In a machine for applying caps to receptacles, a guiding device adapted to hold the cap in alignment with the receptacle, said guiding device being provided with a recess and a thin flange forming one of the walls of said recess, means whereby the edge of the cap is located in said recess so as to surround said thin flange, and means whereby an end of the receptacle is located within the cap while the latter is held in said recess.

4. In a machine for applying caps to receptacles, a guiding device adapted to frictionally hold the cap and receptacle in alignment with each other, said guiding device being provided with a rigid internal guiding projection of arcuate form adapted to lie directly between and contact with the cap and receptacle, means whereby the cap is moved in said guiding device to locate the edge of the cap outside of said projection, and means whereby the receptacle is moved in said guiding device to locate an end of the receptacle at the inner side of said projection.

5. In a machine for applying caps to re-

ceptacles, a guiding device adapted to hold the cap in alignment with the receptacle, said guiding device being provided with a recess and a thin flange forming one of the walls of said recess, means whereby the edge of the cap is located in said recess so as to surround said thin flange, and means whereby an end of the receptacle is located within the cap while the latter is held in said recess, the last mentioned means including a pusher acting on the receptacle to withdraw the cap from said recess.

6. In a machine for applying caps to receptacles, a guiding device adapted to frictionally hold the cap and receptacle in alignment with each other, said guiding device being provided with a rigid internal guiding projection of arcuate form adapted to lie directly between and contact with the cap and receptacle, means whereby the cap is moved in said guiding device to locate the edge of the cap outside of said projection, and means whereby the receptacle is moved in said guiding device to locate an end of the receptacle at the inner side of said projection, the last mentioned means including a pusher adapted to release the cap from said projection.

7. In a machine for applying caps to cylindrical receptacles, a cylindrical guiding device adapted to frictionally hold the cap and receptacle in alignment with each other, said guiding device being provided with an internal flaring flange forming a recess to receive the edge of the cap, means whereby the cap is pushed along said guiding device to locate said edge of the cap within said recess, and means whereby the receptacle is moved to force an end of the receptacle across said flaring flange and into the cap.

8. In a machine for applying caps to cylindrical receptacles, a cylindrical guiding device adapted to frictionally hold the cap and receptacle in alignment with each other, said guiding device being provided with an internal flaring flange forming a recess to receive the edge of the cap, means whereby the cap is pushed along said guiding device to locate said edge of the cap within said recess, and means whereby the receptacle is moved to force an end of the receptacle across said flaring flange and into the cap, the last mentioned means including a pusher acting on the receptacle to withdraw the cap from said recess.

9. In a machine for applying caps to cylindrical receptacles, a cylindrical guiding device comprising gripping jaws adapted to frictionally hold the cap and receptacle in alignment with each other, each of said jaws being provided with a guiding flange on its friction face forming a recess to receive the edge of the cap, means whereby the cap is pushed along said jaws to locate the edge of the cap in the recesses, means where-

by the receptacle is moved along said jaws to force an end of the receptacle across the flanges and into the cap the last mentioned means including a pusher acting on the receptacle to withdraw the cap from the recesses, and means whereby the jaws are moved away from each other to release the guiding flanges from the receptacle.

10. In a carton-capping machine, a guiding device whereby one end of the carton is directed into the cap, said guiding device including a rigid flange disposed within the cap and having a flaring friction face for contracting the cap-receiving end of the 15 carton.

11. In a carton-capping machine, a guiding device whereby the cap-receiving end of the carton is directed into the cap, said guiding device including a rigid flange adapted 20 to lie within the cap, said flange having a flaring friction face adapted to contract the cap-receiving end of the carton, and means whereby said end is forced across said flaring friction face to lie within the cap, said means 25 being adapted to remove the cap from said flange, and said guiding device being movable to separate said flange from the carton.

12. In a machine for applying flexible caps to receptacles, a guiding device adapted 30 to frictionally hold the cap in alinement with the receptacle, the friction face of said guiding device being provided with openings to receive bulging portions of the cap, said friction face also having a guiding flange 35 adapted to direct one end of the receptacle into the cap, and operating means whereby the cap and receptacle are moved along said friction face to locate said guiding flange between the inside of the cap and the outside 40 of the receptacle.

13. In a machine for applying caps to receptacles, gripping members adapted to frictionally hold the cap in alinement with the receptacle, a reciprocating member provided 45 with an upper pusher adapted to push the caps to said gripping members, a lower pusher extending from said reciprocating member to push the receptacles to said gripping members, and a pair of feeders arranged one above the other to feed the caps 50 and cans into the paths of said pushers.

14. In a machine for applying caps to receptacles, gripping members adapted to frictionally hold the cap in alinement with 55 the receptacle, a reciprocating member provided with an upper pusher adapted to push the caps to said gripping members, a lower pusher extending from said reciprocating member to push the receptacles to said 60 gripping members, an endless traveling belt whereby the caps are transmitted to the path of said upper pusher, means for delivering caps to the inner face of said belt, said upper

pusher being movable through said belt, and a lower traveling belt arranged below the 65 first mentioned belt to feed the receptacles into the path of said lower pusher.

15. In a machine for securing caps to receptacles, a capping device adapted to apply the caps to the receptacles, feeding means including a traveling conveyor whereby the receptacles are carried toward said capping device, a stop arranged in the course of the receptacles to permit motion of the belt while some of the receptacles are at rest, and 70 a gumming device including a gum-applying roll arranged over the course of the receptacles to contact with the upper edges thereof, said roll being remote from said stop to prevent stoppage of the receptacle 75 in contact with said roll.

16. In a machine for securing caps to receptacles, a capping device adapted to apply the caps to the receptacles, feeding means including a traveling conveyor whereby the 80 receptacles are carried toward said capping device, a stop arranged in the course of the receptacles to permit motion of the belt while some of the receptacles are at rest, a gumming device including a gum-applying 85 roll arranged over the course of the receptacles to contact with the upper edges thereof, said roll being remote from said stop to prevent stoppage of the receptacle in contact with said roll, and an automatic stop 90 device arranged in the course of the receptacles passing to said roll so as to limit the number of the receptacles between said roll and the first mentioned stop, said automatic stop device including means for releasing 100 one receptacle for each capping operation.

17. In a machine for securing caps to receptacles, a capping device adapted to apply the caps to the receptacles, feeding means including a traveling conveyor whereby the 105 receptacles are carried toward said capping device, a stop arranged in the course of the receptacles to permit motion of the belt while some of the receptacles are at rest, a gumming device including a gum-applying 110 roll arranged over the course of the receptacles to contact with the upper edges thereof, said roll being remote from said stop to prevent stoppage of the receptacle in contact with said roll, a second stop device arranged in the course of the receptacles passing to said roll, so as to limit the number of receptacles between the first mentioned stop and the roll, and means whereby said second stop device is released in response to 115 each operation of the capping device so as to deliver the receptacles to said roll.

In testimony that I claim the foregoing I hereunto affix my signature.

CHARLES W. LOUFEK.
